UNITED STATES PATENT OFFICE.

CHARLES H. HOFFSTETTER, OF ERIE, PENNSYLVANIA.

GAS-STOVE.

No. 824,180.

Specification of Letters Patent.

Patented June 26, 1906.

Application filed August 15, 1905. Serial No. 274,813.

To all whom it may concern:

Be it known that I, CHARLES H. HOFFSTETTER, a citizen of the United States, residing at Erie, in the county of Erie and State of Pennsylvania, have invented new and useful Improvements in Gas-Stoves, of which the following is a specification.

This invention relates to gas-stoves; and it consists in certain improvements in the construction thereof, as will be hereinafter fully described, and pointed out in the claims.

The invention is illustrated in the accompanying drawings, as follows: Figure 1 is a transverse section of the stove, and Fig. 2 is a perspective view of the base of the stove in section. Fig. 3 is a detailed view showing the foot-rest and its means of support.

The body of the stove is formed of the base A, to which the legs B are attached, and the fire-box C. The grate D is arranged in the fire-box and is supplied with some heat-retaining material, such as fire-brick. Beneath the grate is arranged a plurality of burners E E E. Pipes e e e lead to these burners from the mixers e' e' e'. Just outside of the mixers are arranged the valves e² e², and these are connected with the manifold F. The foot-rest G extends along the front of the stove over this manifold. It has extending from it the lug g', by which it is secured to the arms or brackets g. These arms or brackets g are secured to the stove-body. The valve-stems e³ e³ e³ are arranged between the foot-rest and the stove-body and are so exposed that they may be operated. The manifold F rests in a pocket g² at the end of the bracket g. The lug g' is secured to the bracket g by means of the bolt g³, and when so secured it secures the manifold F in place in the pocket g².

In stoves of this character as heretofore made the manifold has been placed at the end, and this position of the valve makes it inconvenient to operate them. By arranging the manifold under the foot-rest not only is the manifold protected, but the stove presents a slight appearance and the valves may be operated from the most convenient point on the stove.

Having thus described my invention, what I claim as new, and desire to secure by Letters Patent, is—

1. In a gas-stove, the combination with

the stove-body, a foot-rest arranged along the front of and supported by the body, a plurality of burners, a manifold arranged under and protected by the foot-rest, and connections between the manifold and the burners.

2. In a gas-stove, the combination with the stove-body, a foot-rest arranged along the front of and supported by the body, a plurality of burners, a manifold arranged under and protected by the foot-rest, connections between the manifold and the burners, valves in said connections, stems for said valves being between the body of the stove and the foot-rest.

3. In a gas-stove, the combination of the stove-body; the bracket g secured to the stove-body; a foot-rest G secured to the bracket; a manifold arranged under the foot-rest and secured in place between the bracket or arm g and the foot-rest as these parts are assembled.

4. In a stove, the combination of the stove-body; a plurality of burners arranged in the body; the bracket g secured to the body and extending therefrom and having the pocket g² therein; manifold F arranged in said pocket extending along the front of the stove; connections from the manifold with said burners; a foot-rest arranged over the manifold and acting with the brackets 4 securing the manifold in place; means for securing the foot-rest to the bracket.

5. In a gas-stove, the combination of the inclosed stove-body, a plurality of burners E, E, arranged in the body, pipes e, e, extending from the burners to the front of the body of the stove, mixers e' e', connected with said pipes, and arranged outside the body, valves e², e², a manifold connected with said valves and extending along the front of the stove-body, a foot-rest G arranged over the manifold and secured to the body of the stove, the stems e³, e³ of the valves extending upwardly between the foot-rest and the body of the stove.

In testimony whereof I have hereunto set my hand in the presence of two subscribing witnesses.

CHARLES H. HOFFSTETTER.
